Fig. 2.

UNITED STATES PATENT OFFICE.

CLARENCE MEDLEY, OF CALGARY, ALBERTA, CANADA.

NON-REFILLABLE BOTTLE.

No. 846,338.

Specification of Letters Patent.

Patented March 5, 1907.

Application filed April 18, 1906. Serial No. 812,503.

To all whom it may concern:

Be it known that I, CLARENCE MEDLEY, of the town of Calgary, in the Province of Alberta, in the Dominion of Canada, have invented certain new and useful Improvements in Non-Refillable Bottles; and I do hereby declare that the following is a full, clear, and exact description of the same.

The objects of the invention are to devise a non-refillable bottle which will allow the contents of the bottle to flow freely therefrom, but will effectually prevent any liquid being returned, either by pouring or by pressure, irrespective of the position in which the bottle is held, to cheapen the manufacture, and to arrange the interior parts of the stopper portion so that they cannot be tampered with; and it consists, essentially, of a disk fitting within the neck of the bottle and having an orifice therethrough, a valve closing said orifice, means for holding said valve to its seat, a cylindrical plug fitting within the neck of the bottle having a recess in the under side thereof and a plurality of openings in communication with said recess, a cap fitting within the neck of the bottle abutting said cylindrical plug, having an orifice therethrough and a recess in the under side thereof in communication with the openings in said plug, and means for retaining said cap within the neck of said bottle.

In the drawings, Figure 1 is a sectional perspective view of the neck of a bottle fitted with my device. Fig. 2 is a perspective detail of the parts of the stopper device arranged relatively one above the other.

Like letters of reference indicate corresponding parts in each figure.

In the drawings, *a* is a bottle having the neck *b* thereof formed with a slightly-tapered portion *c* and the extending portion preferably cylindrical.

d is a disk of glass or other suitable non-absorbent and non-corrosive material fitting loosely within the neck of the bottle and having a central orifice *e* therethrough and an annular groove *f* in the outer periphery, preferably at the lower side.

g is a ring of cork or other suitable compressible material fitting around the lower portion of the disk *d* and filling the groove *f*. The disk *d* is placed in the neck of the bottle and pressed downwardly, pushing the ring *g* slightly into the tapered portion *c* of the neck, and thus making a secure and watertight joint with the said neck. The central

orifice *e* is preferably circular and tapers inwardly from the upper surface, and the under surface is flared outwardly to a point near the edge of the disk.

h is a valve or float, of cork or other suitable material that will float, and is tapered to fit the tapered orifice *e*. The valve or float *h* rests in the said orifice, and the upper surface is flat and normally flush with the top of the disk *d*.

i is a cone-shaped weight, of glass or other suitable material, which rests upon the upper face of the disk *d* and the top surface of the valve *h*, holding said valve down upon its seat and closing the orifice *e*.

j is a cylindrical plug, of glass or like material, fitting loosely within the neck of the bottle and resting upon the disk *d* and having a cone-shaped recess *k* formed in the under side thereof. The recess *k* has the sides thereof parallel with the cone-shaped weight *i*, but a slight distance above the same. The recess *k* extends outwardly to near the outer edge of the under side of the plug, leaving a narrow edge for the said plug to rest upon the disk *d*. *l* are vertical slots formed in the outer periphery of the plug *j* and extending from the top thereof downwardly and communicating with the recess *k*. *m* is a cap, also formed of glass, fitting loosely within the neck *b* and resting upon the top of the plug *j*. The cap *m* has a recess *n* in the under side thereof in communication with the vertical slots *l* in the plug *j* and a central orifice *o* extending upwardly from said recess. The orifice *o* is preferably of small diameter.

p is an annular recess in the outer periphery of the cap *m*, and *q* are vertical slots or openings extending from the said annular recess to the upper surface of said cap.

r is an annular groove formed in the interior of the neck of the bottle and registering with the groove *p* in the cap *m*.

s is a cement filling which is forced through the vertical slots *q* and fills the annular grooves *p* and *r* in a plastic state and when set securely seals the cap in place in the neck of the bottle and prevents the said cap from being removed, and consequently any of the other portions below the said cap.

The bottle is first filled with the liquid which it is to contain and the parts previously described placed in position. A suitable cork may then be inserted in the top portion of the neck to prevent the contents of the bottle from escaping. In order to re-

move the contents of the bottle, the cork is drawn and the bottle tilted in the usual manner. The liquid contained in the bottle will lift the valve *h* from its seat, pushing the cone *i* into the recess *k* in the plug *j* and flow through the slots *l* and the central orifice *o* in the cap *m*. When the liquid has been poured from the bottle and the bottle placed upright, the float *h* will drop into its seat and the cone *i* will drop on top of it.

No liquid can be poured or forced into the bottle after the parts described have been placed in position. When the bottle is in an upright position, the opening *e* is securely closed, and consequently no liquid can enter the bottle from the neck. Should the bottle be tilted on its side, the cone-shaped weight *i* will slip sidewise until the side of the cone comes in contact with the side of the cone-shaped recess *k*, and as the recess *k* is of the same angle as the cone it cannot tilt forward. Thus the flat portion or bottom of the weight *i* remains pressing against the float *h*, holding it securely to its seat.

It will be readily seen that in order to cause the weight *i* to slide away from the disk *d* and allow the float *h* to lift off its seat the bottle must be tilted until the side of the cone-shaped recess is past the horizontal. It will be then be impossible to pour liquid into the bottle. Should liquid be forced into the neck of the bottle under pressure when in an inverted or partially-inverted position, the said liquid will lift the float *h* from the base of the cone, and as the said float is of such a length that even in the inverted position of the bottle the small end does not leave the opening *e* the liquid will lift it upward and cause it to securely close the opening. The greater the pressure the tighter the valve will seal the opening.

The construction of the plug *j* and cap *m* is such that it is impossible to insert a wire or instrument that will hold the float off its seat, as it would be necessary for such wire to pass through the orifice *o*, across the recess *n*, and down one of the vertical slots *l*. The wire would then have to bend at a right angle again in order to pass in far enough to foul the float, and it is apparent and has been found in practice that this is impossible.

A bottle fitted with the stopper attachments herein described will fill a long-felt want and can be furnished at a very small cost. There are no delicate parts to get out of order, and all parts, with the exception of the cork float or valve, may be molded in glass.

What I claim as my invention is—

1. In a device of the class described, in combination with the neck of a bottle having

a tapered portion, a disk fitting within said neck adjacent to said tapered portion having an annular groove in the outer periphery and a central tapered circular orifice therethrough a ring of compressible water-tight material inserted in said groove and abutting the tapered portion of said neck making a water-tight joint, a tapered float-valve fitting the central tapered orifice in said disk and closing the same, a cone-shaped weight resting upon said valve and disk, a cylindrical plug fitting within said neck above said disk and resting thereon having a cone-shaped recess in the under side thereof and a plurality of vertical slots in the outer periphery in communication with the said recess, a cap fitting within said neck and resting on said plug having a central orifice therethrough and a recess in the under side in communication with the vertical slots in said plug, and means for retaining said cap within the said neck, as and for the purpose specified.

2. In a device of the class described, in combination with the neck of a bottle having a tapered portion at the lower end thereof and an annular groove therein intermediate of its length, a disk fitting within said neck adjacent to said tapered portion having an annular groove in the outer periphery and a central tapered circular orifice therethrough, a ring of compressible water-tight material inserted in said groove and abutting the tapered portion of said neck making a water-tight joint, a tapered float-valve fitting the central tapered orifice in said disk and closing the same, a cone-shaped weight resting upon said valve and disk, a cylindrical plug fitting within said neck above said disk and resting thereon having a cone-shaped recess in the under side thereof and a plurality of vertical slots in the outer periphery in communication with the said recess, a cap fitting within said neck and resting on said plug having a central orifice therethrough and a recess in the under side in communication with the vertical slots in said plug and an annular groove in the outer periphery thereof registering with the annular groove in said neck having vertical slots extending upwardly therefrom, and a plastic cement fitting said annular grooves, as and for the purpose specified.

Signed at the town of Calgary, in the Province of Alberta, in the Dominion of Canada, this 30th day of March, 1906.

CLARENCE MEDLEY.
